UNITED STATES PATENT OFFICE.

SAM TIRRITH, OF TOLEDO, OHIO.

HAND-PROPELLED SLED.

Application filed November 1, 1922. Serial No. 598,355.

To all whom it may concern:

Be it known that I, SAM TIRRITH, a citizen of the United States, residing at Toledo, in the county of Lucas and State of Ohio, have invented certain new and useful Improvements in a Hand-Propelled Sled; and I do hereby declare the following to be a full, clear, and exact description of the invention, such as will enable others skilled in the art to which it appertains to make and use the same.

The object of the invention is to provide a simple and efficient sled of the hand propelled type adapted for use either as an amusement device to be made of a comparatively small size for juvenile operation or for utility purposes in localities where snow and ice are prevalent during a considerable portion of the year; and with these objects in view the invention consists in a construction and arrangement of parts of which a preferred embodiment is shown in the accompanying drawing, wherein:

Figure 1 is a side view and

Figure 2 is a plan view of a sled embodying the invention,

Figure 3 is a longitudinal sectional view of the same,

Figure 4 is a transverse section on the plane indicated by the line 4—4 of Figure 3.

The structure embodies essentially the runners 10 which are extended upward at their rear ends to form standards 11 and are connected at their upturned forward ends by an arch 12 to serve as a fender or bumper, a seat frame having side members 13 arranged for support by said runners and provided at its rear end with a seat 14 which may have a suitable back 15, and propelling mechanism which may be manually operated as through the agency of hand levers 16 which are mounted for swinging movement upon a transverse fulcrum bar 17 supported by the runners and suitably braced from the seat frame.

The runners are preferably provided with offsets or lateral extensions 18 forming foot rests for the occupant of the seat and extending from the fulcrum bar longitudinally of the structure to the seat and connected with the latter by hanger rods 19 are guide rods 20 which are arranged in pairs and are parallel to form guides for the push rods 21 which are pivoted at 22 respectively to the hand levers and are provided with

terminal spurs or points 23 for engagement with the surface traversed by the runners.

The retraction of the push rods is effected by means of contractile springs 24 extending thereto from the fulcrum bar or other convenient point of attachment and the guides are preferably provided with supporting rollers 25 which serve to carry the push rods during their return movement under the action of the springs 24 to prevent the dragging of the terminal spurs 23 on the surface supporting the vehicle. Also each push rod is preferably provided with lateral guide rollers 26 serving to minimize friction in the reciprocatory movement of said rods by contact with the members of the guides. Each of the rollers 25 is carried by a suitable support 27 having a vertically disposed portion 28 journaled in the side member 13 and in a bracket 29 suspended from the side member. The supports 27 have inwardly directed portions 30 at their upper ends and springs 31 are connected with the portions 30 and with the seat 14 and serve to return the support and their rollers to their normal position when they are moved from such position.

On forward movement of the sled under power applied in the proper manner to one of the handles 16 the active push rod 21 will be engaged by its respective roller 25 and the roller and its support will be swung on their pivot and will permit the passage of the push rod. As soon as the push rod passes the roller, the roller will be returned to its normal position by the spring 31. Forward movement of the push rod will then bring it into contact with the roller and the push rod will be elevated.

It will be obvious that by an alternate oscillatory movement of the hand levers by the occupant of the seat 14 a continuous forward motion may be imparted to the sled at any desired speed within the ability of the operator to vigorously and rapidly actuate said levers, and as the push rods are arranged in side by side relation it will be obvious that the guiding or steering of the vehicle may be effected by a slightly stronger impulse being applied to one hand lever or the other according to the direction in which it is desired to progress.

The structure disclosed may be used either as an amusement device for children or in the proper sizes may be employed for gen-

eral transportation purposes in lieu of other types of vehicles, either for business or pleasure and under such conditions as to afford opportunities for pleasurable exercise.

Having thus described the invention, what I claim as new is:—

1. A self propelled sled having runners provided with rear standards and connected at their front ends by an arch forming a fender, a transverse fulcrum rod, a centrally open frame surmounting the runners with a seat located at its rear end, longitudinal brace rods extending from the rear of the frame to the fulcrum rod and arranged in parallelism to form guides, hand levers fulcrumed upon said fulcrum rod with their free ends within reach of the occupant of the seat, and terminally spurred push rods pivotally connected to the hand levers and extending downwardly and rearwardly between said guides to engage the surface traversed by the runners.

2. A self propelled sled having runners provided with rear standards and connected at their front ends by an arch forming a fender, and also provided with lateral extensions forming foot rests, a transverse fulcrum rod, a centrally open frame surmounting the runners with a seat located at its rear end, longitudinal brace rods extending from the rear of the frame to the fulcrum rod and arranged in parallelism to form guides, hand levers fulcrumed upon said fulcrum rod with their free ends within reach of the occupant of the seat, and terminally spurred push rods pivotally connected to the hand levers and extending downwardly and rearwardly between said guides to engage the surface traversed by the runners.

3. A self propelled sled having runners provided with rear standards and connected at their front ends by an arch forming a fender, a transverse fulcrum rod, a centrally open frame surmounting the runners with a seat located at its rear end, longitudinal brace rods extending from the rear of the frame to the fulcrum rod and arranged in parallelism to form guides, hand levers fulcrumed upon said fulcrum rod

with their free ends within reach of the occupant of the seat, and terminally spurred push rods pivotally connected to the hand levers and extending downwardly and rearwardly between said guides to engage the surface traversed by the runners, contractile springs being connected with the push rods for retracting the same after each operative stroke.

4. A self propelled sled having runners provided with rear standards and connected at their front ends by an arch forming a fender, a transverse fulcrum rod, a centrally open frame surmounting the runners with a seat located at its rear end, longitudinal brace rods extending from the rear of the frame to the fulcrum rod and arranged in parallelism to form guides, hand levers fulcrumed upon said fulcrum rod with their free ends within reach of the occupant of the seat, and terminally spurred push rods pivotally connected to the hand levers and extending downwardly and rearwardly between said guides to engage the surface traversed by the runners, rollers provided in the guides for carrying the push rods during their return movement.

5. A self propelled sled having runners provided with rear standards and connected at their front ends by an arch forming a fender, a transverse fulcrum rod, a centrally open frame surmounting the runners with a seat located at its rear end, longitudinal brace rods extending from the rear of the frame to the fulcrum rod and arranged in parallelism to form guides, hand levers fulcrumed upon said fulcrum rod with their free ends within reach of the occupant of the seat, and terminally spurred push rods pivotally connected to the hand levers and extending downwardly and rearwardly between said guides to engage the surface traversed by the runners, the push rods being provided with anti-frictional guide rollers for contact with the sides of said guides.

In testimony whereof I affix my signature in presence of two witnesses.

SAM TIRRITH.
